KEY STROKE COUNTING MECHANISM

Harvey N. Bliss, Hartford, Conn., assignor to
Veeder-Root, Incorporated, a corporation of
Connecticut

Application January 10, 1930, Serial No. 419,936

8 Claims. (CL 235—102)

My invention relates to key stroke counting mechanism.

It has for its object to provide an improved mechanism adapted to be applied to a writing machine, such as a typewriter, tabulator, or the like, and operable upon the actuation of any printing key or the space bar thereof to count the number of strokes of the same. A further object of my invention is to provide improved actuating mechanism for such a counter whereby the same may be actuated with a minimum load on the keys and actuated in such manner as to insure accurate operation irrespective of variations in the stroke of different keys or of variations in the touch of an operator or of different operators. Still further objects include the provision of improved counter actuating and controlling means and improved counter supporting means. These and other objects and advantages of my improved construction will however hereinafter more fully appear.

In the accompanying drawing I have shown for purposes of illustration two embodiments which my invention may assume in practice.

25 In the drawing,—

Figure 1 is a front elevation of one form of the same shown in position on a machine, only portions of the latter being shown to simplify illustration.

30 Fig. 2 is a rear elevation with the operating parts shown in another position in dotted lines.

Fig. 3 is an end view of the structure shown in Figure 2.

35 Fig. 4 is an enlarged partial end view showing the parts in a position corresponding to the dotted line position shown in Figure 2.

Fig. 5 is a front view similar to Figure 1 and showing a front elevation of a modified construction.

40 Fig. 6 is a plan view of this structure.

Fig. 7 is an end view with the operating parts shown in another position in dotted lines.

Fig. 8 is an enlarged partial end view showing the parts in a position corresponding to that shown in dotted lines in Figure 7.

45 Fig. 9 is a detailed sectional view on line 9—9 of Figure 8.

In each of these illustrative constructions I have shown key stroke counter mechanism of the general type described and claimed in my co-pending application Serial No. 419,934, filed January 10, 1930, the present constructions constituting modifications of the structure shown therein whereby the latter are improved and adapted 50 to use in different relations.

Considering first the construction shown in Figures 1 to 4, it will be noted that I have shown, as before, a counter 1 comprising a series of counter wheels 2 visible through a reading aperture 3 in the counter casing and operatively connected to a shaft 4 carrying a pivoted actuating member 5, while a combined ratchet actuating and friction retaining clutch mechanism 6 is provided between this lever 5 and the counter wheels. Also, it will be noted that as in my previously mentioned case, I have shown lugs 7 disposed in the path of the lever 5 and operative to limit the possible movement thereof to a predetermined fractional advance of the counter, as for example an advance of one-tenth of a unit for each complete 10 operation of the member 5. Moreover, it will be understood that herein, as in my application referred to, the lever 5 moves freely from the position shown in Figure 3 and does its work of actuating the counter wheels on its return stroke from the position shown in Figure 4 to that shown in 20 Figure 3.

Considering the structure more in detail, it will be noted that the reading aperture 3 herein is disposed at an angle of approximately 45 degrees to the plane of a depending bracket member 8 formed on the casing. It will also be noted that this bracket member is attached by screws 9 to a cooperating bracket member having an upstanding portion 10 disposed parallel to the axis of the counter and extending above and below the latter and also having a pair of laterally extending spaced extensions 11 underlying the machine frame 12 and connectible thereto by suitable screws 13. Here it will also be noted that the portion 10 of this bracket has the lugs 7 formed directly thereon and that these lugs are disposed above and below between the ends of the lever 5, see Figure 4, while the outer end of the latter is operatively connected to improved key stroke operating mechanism.

More particularly considering the latter mechanism, it will be noted that a lever 15 is extended along the bracket portion 10 and pivoted thereon at one end, as at 16, at a point remote from the counter. It will also be noted that the upper edge of the front end of this lever is engageable with the upper wall 17 of a notch formed in the underside of the outer end of the lever 5 just outside the portion of the lever 5 which engages the lugs 7. As herein a coiled spring 18 is also preferably connected to the outwardly extending lug 19 thus provided on the lever 5 above the surface 17, and this spring 18 has its lower end connected to a lateral extension 20 on the bottom of the free end 25

of the lever 15. Thus, it will be evident that whenever the lever 15 is depressed as by the operation of a printing key or the space bar, the lever 5 will be pulled down by the spring 18 within the limit established by the lower lug 7 to the position indicated in Figure 4, whereas when the member 15 is moved oppositely about its pivot upon the release of the key or the space bar, the member 5 will be returned to initial position shown in Figure 3, i. e. against the upper lug 1.

Associated with the member 15 and operative to move it about its pivot is herein a connected lever 25 extending upwardly from the pivot 16 and preferably integrally united with the member 15 and forming therewith a bell crank lever. Herein this member 25 also has its upper end provided with a protruding abutment face 26 engageable with the universal bar 27 of the machine, which bar is as usually operative upon each key stroke or each operation of the space bar. It will also be noted that herein I have provided a coiled spring 28 which is connected between a laterally extending pin 29, carried on the portion 10 of the bracket above the member 15, and a laterally extending lug 30 on the latter member, this spring being located between the pivot 16 and the lug 20 but nearer the latter. Herein, this spring 28 acts to return the levers 15 and 25 to the initial position indicated in full lines in Figures 2 and 3. To prevent abuse I may, as herein, also provide a pin 31 on the portion 10 projecting into the path of the member 15 between the lug 30 and pivot 16.

In the operation of the mechanism, it will be evident that whenever the universal bar is operated, the member 25 and the connected member 15 will be moved from the full to the dotted line position illustrated in Figure 2. As a result, through the spring 18, the lever 5 will be moved from the position shown in Figure 3 to the position shown in Figure 4, i. e. between the limits established by the lugs 1. When, however, the universal bar moves backward automatically in the operation of the machine, i. e. on release of the key or space bar, the members 25 and 15 will be moved by the spring 28 to the full line position illustrated in Figure 2, and move the arm 5 through its counter actuating or working stroke, i. e. from the position shown in Figure 4 to the position shown in Figure 3. It will also be evident that irrespective of variations in the stroke of any of the connected mechanism, the lever 5 will be moved through the desired amount to provide an accurate count. Moreover, it will be evident that over-travel is permitted the member 15 or any of the connected mechanism without disturbing the accuracy of the count. It will also be noted that in one direction of movement the front end of the member 15 will move away from the member 5, and that the latter will be pulled down by the spring 18 until it engages the lower stop 7, while in the return operation, under the action of the spring 28, the front end of the member 15 will engage the surface 11 on the member 5 and positively lift the latter.

Considering the construction shown in Figures 5 to 9, it will be noted that the counter is arranged substantially as previously described with respect to its support, and that it has a similar bracket 8 attached by similar screws 9. Herein, however, it will be observed that bracket 8 rests against a vertically disposed flat bracket member 40 having a lateral extension 41 thereon provided with lugs 42, correspond-

ing to the lugs 7 and forming the lever engaging notch 44. It will also be noted that this member 40 has a co-operating clamping plate 45 attached thereto by screws 46 extending through the frame 47 of the machine, and that the two plates overlap the ends of a suitable opening 48 in the machine frame as shown in Figures 5 and 7, so that the counter may be readily, quickly, and securely clamped in position.

It will also be noted that herein a coiled spring 49 is connected to the outer end of a laterally extending pin 50 carried on the lever 5 at a point between the lugs 42 and the axis of the lever. This spring also extends downwardly as illustrated in Figure 7 and is connected at its lower end to an upstanding extension 51 on an actuating member 52. As shown, this member 52 is also provided with a higher upstanding portion 53 engageable with the underside of the lever 5 and located at one side of its portion 51 and extending upward toward the lever 5 as illustrated in Figures 8 and 9 at a point substantially under the pin 50. This member 52 is herein also provided with a laterally extending portion 54 extending inside the frame beneath the lower lug 42 and with an upwardly inclined and then a laterally disposed portion on its inner end. The latter portion is also provided with a bent over portion 56 adapted to engage a part 54 of the machine escapement bracket and be clamped thereto by suitable means as for example, a screw 55.

In operation it will be evident that the escapement bracket being movable with each operation of any printing key or the space bar, the member 52 will then be moved from the full to the dotted line position shown in Figure 7 in such manner as through the spring 49 to pull down the lever 5 from the position shown in Figure 7 to the position shown in Fig. 8. It will also be evident that when the key or space bar is released, the escapement bracket and the connected mechanism mentioned, will be returned by the machine to the upper position in Fig. 7. It will also be observed that through the use of the spring 49 any desired over-travel arising from a longer stroke of any key or part of the connected mechanism will be permitted while the lever 5 will be operated in such manner as to insure an accurate operation of the counter irrespective of such variations. Further, it will be evident that where the touch of the operator varies, this over-travel mechanism will function similarly. It will also be evident that whenever the stroke of the member 52 exceeds the limit of the stroke permitted lever 5 the spring 49 will assist in the return of the parts during that part of the return stroke previous to the engagement of portion 53 with lever 5 and that the portion 53 will also have a function corresponding to that of the front end of the lever 15 which in my previously described construction, engages the upper wall 17 of the notch provided in the outer end of the lever 5, although in the present construction, no such notch is provided.

The term "writing machine" occurring in the claims is used herein in a generic sense to include typewriters, tabulators, or the like, and is intended to cover any machine in which manually operated keys are utilized for performing operations on a machine regardless of whether the manual operations are for actuating char-

acter forming keys, space bars, or for other operative functions of the machine.

While I have in this application specifically described two embodiments which my invention 5 may assume in practice, it will be understood that these forms of the same are used for purposes of illustration and that the structure may be modified and embodied in other forms without departing from its spirit or the scope of the 10 appended claims.

What I claim as new and desire to secure by Letters Patent is:—

1. Actuating mechanism for a counter applied to a key operated writing machine and having a swinging operating arm element limited in its travel in both directions, said mechanism comprising transmitting members between said element and a reversely movable element of the machine, one of said transmitting members having lost motion operating relation to said arm element, another of said members being a resilient pull member, said mechanism being operative on movement of said second element in one direction to move said arm element in one direction by said pull member from one of its travel limits to the other, with said pull member permitting overtravel of said second element, and said first transmitting member being operative to effect a return movement of said arm element from said other travel limit to the first named limit by directing engagement of said member with said arm element.

2. Actuating mechanism for a counter applied to a key operated writing machine and having a swinging operating arm element limited in its movement in both directions and having a free end, said mechanism comprising transmitting members between said arm element and a reversely movable element of the machine, one of said members having lost motion contact engagement with the free end of said arm element, another of said members comprising a resilient pull member connecting the first member with the end of said arm element, said mechanism being operative on movement of said second element in one direction to move said arm element in one direction by said pull member from one of its travel limits to the other, and said first transmitting member being operative to effect a return movement of said arm element by direct actuation thereof.

3. Actuating mechanism for a counter applied to a key operated writing machine and having a swinging operating arm element limited in its travel and having a free end, said mechanism comprising a swinging member operated in opposite directions upon movement in opposite directions of an actuating reversely movable element of the machine and having lost motion contact engagement with said arm element and movable angularly independently of said element, and resilient pull means extending between and connecting said swinging member to said arm element and moving said arm element in one direction through said resilient pull means, said swinging member moving said element in the opposite direction by direct engagement therewith.

4. Actuating mechanism for a counter applied to a key operated writing machine and having a swinging operating arm with a free end limited

in its travel, said mechanism comprising a swinging member operated in opposite directions upon movement in opposite directions of an element of the machine, said swinging member having a free end and a portion at said end disposed 5 transversely to and adjacent the free end of said arm and adapted to contact and push said arm laterally to actuate the same in one direction, and yielding connecting means between the free end of said arm and the free end of said member by 10 which said arm is moved in the opposite direction.

5. Actuating mechanism for a counter applied to a key operated writing machine and having a swinging operating arm element with limited 15 travel, said mechanism comprising a member swinging in a plane transverse to said arm element and movable in one direction by a movable element of the machine, a spring connecting said member with a fixed part of the machine 20 and urging said member in the opposite direction, said member having a free end extending adjacent the free end of said arm element and adapted to contact and push said arm element in one direction, and a spring connecting said 25 swinging member with said arm element for actuating the latter in the opposite direction.

6. Actuating mechanism for a counter mounted on a bracket on a key operated writing machine and having a swinging operating arm element with limited travel, said mechanism comprising a bell crank lever pivoted on the bracket and operated in one direction by contact with a movable element of the machine, a spring connecting said member and said bracket for re- 30 turning said bell crank lever to its initial position, said bell crank lever having a free end extending adjacent and adapted to engage and push said arm element to actuate it in one direction, and a spring interconnecting said arm element and said lever and adapted to pull said arm element to move it in the opposite direction.

7. Actuating mechanism for a counter applied to a key operated writing machine and having a swinging operating arm element limited in its 45 travel, said mechanism comprising a swinging member swung in opposite directions by an element of the machine, said swinging member being movable in a plane in which said arm element swings and having a free end adapted 50 to engage and push said arm element to actuate it in one direction, and a spring interconnecting said arm element and said member and adapted to pull said arm element to actuate it in the opposite direction.

8. Actuating mechanism for a counter applied to a key operated writing machine and provided with a swinging operating arm having a free end with limited up and down travel, said mechanism comprising a swinging member having a 60 free end moved up and down by opposite movements of an element of the machine, said swinging member being mounted to swing in a plane in which said arm swings and having an upturned transverse portion at its free end underlying 65 and adapted to contact the free end of said arm and actuate said arm by lifting the same, and a spring connecting the free end of said arm with the free end of said swinging member for effecting downward actuation of said arm.

HARVEY N. BLISS.

CERTIFICATE OF CORRECTION.

Patent No. 2,044,202.

June 16, 1936.

HARVEY N. BLISS.

It is hereby certified that error appears in the printed specification of the above numbered patent requiring correction as follows: Page 2, first column, line 19, for the word "usually" read usual; line 29, for "intial" read initial; page 3, first column, line 31, claim 1, for "directing" read direct; and that the said Letters Patent should be read with these corrections therein that the same may conform to the record of the case in the Patent Office.

Signed and sealed this 15th day of September, A. D. 1936.
